UNITED STATES PATENT OFFICE

2,546,278

SOUND REPRODUCING SYSTEM

Roy William Skene, Rouyn, Quebec, Canada

Application September 1, 1944, Serial No. 552,271

3 Claims. (Cl. 250—20)

1

This invention relates to radio receiving and reproducing apparatus, and more particularly to electrical apparatus adapted to suitable control thereof when interposed in the electrical circuit between any radio receiver and radio reproducers of the special acoustical type known to the art as pillow speakers, or in the circuit between any electrical device the output current of which is in the form of electrical oscillations which have been modulated for sound reproduction, and the acoustic apparatus in which said modulated electrical impulses are converted into audible sound, whether the said electrical devices are remote from one another or in close proximity.

One object of my invention is to provide a suitable method of remote control for pillow speakers by means of which the person using same may switch it into, or out of the output circuit of a radio receiver at will without the necessity of going from the pillow speaker to the radio receiver, which may, or may not be in the same room or on the same floor.

A further object is to provide a separate control unit which may be placed on a table or chair beside a couch or hospital bed within easy reach of the person who is using a pillow speaker, thus affording the user individual control of the pillow speaker while remaining in a comfortable reclining position, for use in hospitals, apartments or homes where it is desirable that radio programmes may be enjoyed at will by some, without causing any inconvenience to others.

Another object of my invention is to provide a separate portable control unit adapted to plug into any radio receiver or similar device, which includes suitable outlets for such use, thus extending its usefulness to more than one radio receiver.

Those which were not manufactured for this purpose may easily be modified by any person skilled in radio servicing.

Still another important object of my invention is to provide a suitable electrical circuit which may be built into radio receivers by the manufacturer for the control of pillow speakers remote from the receiver, and which may be used alone or in conjunction with a portable individual control unit, making it possible to use the receiver in one room and a pillow speaker wired to another room, each separately or at the same time as may be desired.

An equally important object is to provide a control unit which may be used for the purpose of transferring telephone calls from one telephone to an extension telephone on the same line or in the same building.

2

With the above noted and other objects in view which may appear as the description proceeds the invention resides in the novel construction, combination and arrangement of co-operating parts as hereinafter more specifically set forth, claimed and shown in the accompanying drawings forming part of this application, and in which:

Figure 1 is a circuit diagram of the apparatus. Figure 2 is a circuit diagram of a modified form

10 of the apparatus.

Figure 3 is a modified circuit diagram of the apparatus as used in a push-pull output circuit and using transformer coupling to pillow speaker.

Figure 4 is a partial circuit diagram as above 15 but using condenser coupling to pillow speaker as an alternative.

Figure 5 is a circuit diagram of the apparatus, and similar to Figure 1, except that condenser coupling to pillow speaker is used in place of 20 transformer.

Figure 6 is a modified circuit diagram of the apparatus similar to Figure 2, as used in a push-pull output circuit and using transformer coupling to pillow speaker.

Figure 7 is a partial circuit diagram as above, but using condenser coupling to pillow speaker as 25 alternative to transformer coupling.

Figure 8 is a circuit diagram of the apparatus similar to Figure 2, except that condenser coupling to pillow speaker is used in place of transformer.

Referring to the drawings in greater detail 30 circuit connection to any radio receiver may be made by providing suitable terminals 8, in the output circuit between the last audio tube 9 and the output transformer 10, so that the modulated output current is routed through the control switches 11 and 12 before passing to either the radio receiver speaker 14, or the pillow speaker 7. Having thus channeled the output current 35 through the control switches, selective control is accomplished by operating switches 11 and 12 to direct the output current from the radio receiver through the radio receiver speaker 14 alone, or through the pillow speaker 7 alone, or through both together as desired. In the circuit shown in Fig. 1 the switch 11 is a double-pole-double-throw switch and consists of movable contacts 11a connected as shown to the output

40 circuit of the radio receiver and stationary contacts 11b and 11c respectively connected to the circuits of the speakers 14 and 7. The switch 12 is a double-pole-single-throw switch and consists of movable contacts 12a connected as shown to the circuit of speaker 14, and stationary con-

45

50

55

tacts 12b connected to the circuit of the speaker 7. When the movable contacts 11a of switch 11 are engaged with stationary contacts 11b and switch 12 is open the speaker 14 will operate alone. With the contacts 11a engaged with contacts 11c and switch 12 open the speaker 7 will operate alone. When contacts 11a of switch 11 are engaged with either the contacts 11b or 11c and with switch 12 closed, the speakers 14 and 7 will operate in unison. Switch 11 is of the type known in the art as a shorting switch, in order to prevent injury to the tubes of the radio receiver due to voltage surge. An audio transformer 13 may be included in the circuit of speaker 7 to match impedance of the pillow speaker if not included in the latter. A variable resistance volume control 15 is also included in the circuit of speaker 7 to control the sound level of the speaker 7 only. In addition an electrostatic fixed condenser 16 may optionally be connected across the secondary terminals of audio transformer 13, as required. The switches employed may be of the toggle type or any other type which will accomplish the same result.

Referring to Figure 2, the control switches 17 and 24 are preferably single-pole-triple-throw switches ganged on the same shaft to operate in unison. The switches 17 and 24 have a movable contact 17a and 24a connected as shown to the output circuit of a radio receiver. The switches are connected together so the movable contacts move in unison to selectively engage stationary contacts 17b, 17c, 17d and 24b, 24c, 24d. The contacts 17b and 17c of switch 17 are dead and contact 17d is connected to the circuit of speaker 14. The contact 24b of switch 24 is connected to the circuit of speaker 14 and contacts 24c and 24d are connected to the circuit of speaker 7. When the switches 17 and 24 are in the position shown in Fig. 2 the circuit of speaker 14 will be closed and the circuit of speaker 7 open. With the switches engaged with contacts 17c and 24c the circuit of speaker 7 will be closed and the circuit of speaker 14 open. When the switches are engaged with contacts 17d and 24d the circuits of speakers 14 and 7 will both be closed and the speakers will operate in unison.

Referring to Figure 3, an arrangement similar to that shown in Figure 1, is diagrammatically represented, showing the adaptation to a receiver having push-pull output tubes 19, and transformer 20, connection to the receiver being made in this case in the transformer secondary leads at 21.

In Figure 4, the use of condenser coupling to pillow speaker is shown as an alternative method, condenser 22, in series and resistor 23, in shunt replacing the audio transformer 13, in a circuit otherwise the same as Figure 3.

In Figure 5, the circuit is the same as Figure 1, except condenser coupling to pillow speaker is used to replace audio transformer 13.

Figures 6 and 7 illustrate diagrammatically the

same alternative speaker couplings as described above in Figures 3 and 4, but using single control switch 17, as shown in Figure 2. Figure 8 again shows condenser coupled pillow speaker with single control switch and single output tube as previously shown in Figure 2, except the coupling condenser 22, and resistor 23, replace the audio transformer 13. By using condenser coupling savings in cost and weight and greater simplicity may be obtained.

It is believed that the construction and advantages of the structure shown may be apparent from the foregoing paragraphs taken in conjunction with the accompanying drawings without further detailed description.

While the preferred embodiment of the invention has been disclosed it is understood that minor changes in the details of construction, combination and arrangement of co-operating parts may be resorted to within the scope of what is claimed without departing from the spirit of the invention.

Having thus given a true and complete description of my invention, what I claim is:

1. In combination a radio receiver, a pair of speaker circuits, a double-pole-double-throw switch for selectively connecting the speaker circuits to the output circuit of the radio receiver having its movable contacts connected to the output circuit of the radio receiver and its stationary contacts respectively connected to the speaker circuits, and a double-pole-single-throw switch having its movable contacts connected to one of the speaker circuits and its stationary contacts connected to the other speaker circuit, said double-pole-single-throw switch, when closed, connecting the speaker circuits to operate in unison when said double-pole-double-throw switch is closed on either side.
2. The combination as described in claim 1 including a variable resistance in the circuit of one of the speakers.
3. The combination as described in claim 2 including an audio transformer in the circuit of one of the speakers.

ROY WILLIAM SKENE.
